US00D618770S

(12) **United States Design Patent**
Hoernig et al.

(10) **Patent No.:** **US D618,770 S**
(45) **Date of Patent:** **** Jun. 29, 2010**

(54) **SHOWER SYSTEM**

(75) Inventors: **Victor Hoernig**, Lowell, IN (US); **Man Ki Yoo**, Skokie, IL (US)

(73) Assignee: **Masco Bath Corporation**, Moorestown, NJ (US)

(**) Term: **14 Years**

(21) Appl. No.: **29/341,763**

(22) Filed: **Aug. 12, 2009**

(51) LOC (9) Cl. **23-02**

(52) U.S. Cl. **D23/283**

(58) Field of Classification Search **D23/275, D23/283, 273, 303-305, 279; 4/663, 552, 4/614, 900**

See application file for complete search history.

(57) **CLAIM**

The ornamental design for a shower system, as shown and described.

DESCRIPTION

FIG. 1 is a front/right side perspective view of a shower system in accordance with an embodiment;

FIG. 2 is a front/left side perspective view of the shower system of FIG. 1;

FIG. 3 is a front elevation view of the shower system of FIG. 1;

FIG. 4 is a top plan view of the shower system of FIG. 1; and, FIG. 5 is a top plan view of a shower system in accordance with another embodiment.

The broken lines are for illustrative purposes only and form no part of the claimed design.
